ANODE STRUCTURE FOR AN ELECTRON
DISCHARGE DEVICE FOR ULTRA HIGH
FREQUENCIESPaul Georges Chevigny, New York, N. Y., assignor
to Federal Telephone and Radio Corporation,
Newark, N. J., a corporation of Delaware

Application December 24, 1942, Serial No. 470,060

4 Claims. (Cl. 250—27.5)

1

This invention relates to improvements in electron discharge devices, and more particularly to vacuum tubes for use at high frequencies.

All vacuum tubes possess certain inter-electrode capacities which, at ultra-high frequencies, in particular, must be taken into careful consideration. In many instances, moreover, the inter-electrode capacity of the tube is a limiting factor with regard to the frequencies at which the tube may operate. A convenient type of tube which has been designed and which is now quite widely used for high frequency work is one in which a centrally disposed cathode is surrounded by a concentric grid which, in turn, is surrounded by a ring-shaped anode. The grid connection is in the form of a thin circular disk protruding from the glass envelope radially of the tube, while the anode lead is in the form of a thicker disk longitudinally spaced from the grid disk and also extending outwardly through the envelope. The glass envelope is, in this case, preferably sealed to the thick anode disk through the use of suitable annular knife edges. While such tubes provide short leads, important in high frequency work, the question of inter-electrode capacities arises, particularly between the grid and the extension of the anode which leads to the disk, and between the grid and the knife edges.

It is the primary object of the present invention to provide a structure which substantially reduces this interelectrode capacity between the grid and anode.

This invention contemplates a construction by means of which the anode disk is longitudinally displaced relatively to the grid, while the position of the anode itself about the grid remains the same.

A preferred construction of such a tube is described below and has been illustrated, by way of example, in the accompanying drawings, in which:

Fig. 1 is an elevation, partially in section of a preferred form of vacuum tube in accordance with the present invention; and

Fig. 2 is a partial cross-sectional view illustrating, for the sake of contrast, a construction of a similar tube without the advantages of the present invention.

The vacuum tube illustrated in Fig. 1, generally indicated at 10, may be of the triode type having a ring-shaped anode 12 concentric with and surrounding an annular grid 14, preferably formed of a plurality of spaced tantalum wires which, in turn, surrounds a cathode in the form of filament 16. The filament 16 may be supplied

2

with power through oppositely spaced leads 18 and central lead 20, extending through and supported by the upper portion of the glass envelope 22. The grid wires 14 are preferably supported about their periphery by a suitable metal cylinder 23 connected to the grid lead in the form of disk 24 extending radially from the tube between the glass envelope sections 22 and 26.

The anode lead is in the form of a thick ring 10 or disk 28 extending radially outwardly from the tube between the glass envelope sections 26 and 30 and sealed thereto by annular knife edges 32 and 34 projecting into the glass. In order to provide a low resistance path between the anode 12 surrounding the grid 14 and the annular anode lead 28, the two are preferably formed integrally and, in accordance with the present invention, the connection between the anode 12 and the anode lead 28 is effected by means of a reversely 15 curved annular section 36 which longitudinally displaces the anode lead 28 and with it the knife edge 32 from the grid 14 and its supporting cylinder 23. The annular section 36 is shaped to have a point of inflection; that is, a change in 20 curvature from concave to convex or conversely depending on the angle at which the tube is considered. By reason of this gooseneck construction it will be noted that the distance between the anode 12 and its ring-shaped lead 28 from the 25 grid 14 and supporting cylinder 23 has been greatly increased in comparison to a structure in which the anode 12 and its lead 28 are in the same plane. At the same time, the distance from the grid 14 and supporting cylinder 23 from the knife 30 edge 32 has also been increased.

The improvement effective by reason of the present invention can, perhaps, be best realized by comparing the construction illustrated in Fig. 2 with the construction in accordance with the 40 present invention in Fig. 1. In Fig. 2 the anode 12' extends radially outwardly to form the annular anode lead 28'. The connecting portion 36' between the parts 12' and 28' is in relatively close proximity to the grid 14 and its supporting cylinder 23, thus creating a relatively large capacity 45 between these parts, which is the same as increasing the grid-anode capacity. Additionally, in the usual construction shown in Fig. 2 the annular knife edge 32' projecting into the glass envelope section 26 directly surrounds the grid support 23 with a resulting large capacity between these parts, which capacity also increases the effective 50 grid-anode capacity, indicated in Fig. 2 as C_{pg} . It will, at once, be clear to those skilled in this 55 art that the construction illustrated in Fig. 1

effects a reduction not only of the capacity between the grid and the interconnecting section between the portions 12 and 28 of the anode, but also by the longitudinal displacement of the annular knife edge 32 substantially below the grid and supporting cylinder. This capacitative effect has been also substantially eliminated.

While the invention has been illustrated in connection with a certain specific type of tube, it is clear that the principles of this invention are applicable to other types of tubes, in which it is desired to bring out the anode lead substantially radially through the tube envelope. The invention is also obviously applicable to tubes containing more than one grid.

For example, in certain types of tubes it is desirable to extend the grid lead out through the tube at the opposite end from the cathode lead or, in the form shown in Fig. 1 through the bottom of the tube. In such a case, the gooseneck would be reversed and the anode lead 28 would be positioned, above the main anode portion 12 rather than below. In this case, there would result a slight increase in the anode-cathode capacitance but this would be more than offset by the comparative decrease in the anode-grid capacitance.

Accordingly, while I have described above the principles of my invention in connection with the specific type of tube, it is to be clearly understood that this description is made only by way of example and not as a limitation on the scope of my invention as set forth in the objects and in the accompanying claims.

I claim:

1. A vacuum tube, including a cathode, a grid surrounding said cathode, a substantially ring-shaped anode surrounding said grid, glass envelope means surrounding said electrodes, said ring-shaped anode having an integral annular extension protruding outside of said envelope, an annular knife-edge on said extension projecting into and forming a seal with the envelope, and an integral anode section shaped to have a point of inflection connecting the ring-shaped anode with its annular extension and longitudinally displacing said annular extension and said knife-edge from said grid.

2. A vacuum tube including a cathode, a grid surrounding and concentric with said cathode, a substantially cylindrical support for said grid, a ring-shaped anode surrounding and concentric with said grid, glass envelope means enclosing said electrodes, said ring-shaped anode having an annular extension projecting outside of said envelope, said annular extension being provided

with a substantially cylindrical knife-edge coaxial with said grid and grid support and projecting into and forming a seal with said envelope, and an integral anode section shaped to have a point of inflection interconnecting the ring-shaped anode with its annular extension, said anode section longitudinally displacing said anode extension and cylindrical knife-edge away from said grid and grid support.

- 10 3. An electron discharge device including, in combination, a centrally positioned cathode, an annular grid surrounding said cathode, a cup-shaped anode whose bottom has substantial thickness and is provided with a central opening 15 about the grid and whose rim is provided with an outward lip, an outwardly extending flange integral with the lip of the cup-shaped anode, two annular knife edges integral with said flange, one being positioned on each side of said flange, a first 20 envelope section closing one end of said electron discharge device and sealed to one of said knife edges, and a second envelope section closing the other end of said electron discharge device and sealed to the other annular knife edge.
- 25 4. An electron discharge device comprising a cathode, a grid surrounding said cathode, and a substantially cup-shaped anode provided with an aperture in the bottom portion, said anode being mounted with the walls of said aperture 30 spaced from and immediately surrounding said grid, an envelope surrounding said cathode, grid and anode, a grid disc connected to said grid and sealed through said envelope at a point adjacent said bottom portion of said anode, an anode disc 35 substantially parallel to said grid disc and sealed through said envelope, said anode disc being connected to said cup-shaped anode at a point remote from said bottom portion whereby said anode disc is longitudinally displaced from said 40 grid and said disc.
